UNITED STATES PATENT OFFICE.

EDWARD HUTCHENS, OF MILWAUKEE, WISCONSIN.

PULP-FORMING PRESS.

Application filed April 2, 1926. Serial No. 99,216.

This invention relates to the manufacture of articles from paper stock or pulp.

It is an object of this invention to provide mechanism for manufacturing a variety of articles such as, for example, stool and toilet seats from chemically treated pulp made from waste paper or the like. The material itself, and the resulting product, forms no part of the present invention which 10 relates to the apparatus used in the process of manufacturing such articles by compressing and drying or baking the pulp in suitable molds.

It is another object of this invention to 15 provide an improved hydraulic piston having a filter plate head with water discharge and vacuum connections leading from beneath said filtering plate.

Heretofore, horizontally arranged hydraulic presses have been used to form articles from paper pulp, but such an arrangement of the press results in an article with the lower side more dense due to settlement 20 of the pulp in the water before and during the pressing operation. Further wire cloth or fine screens have been used as a filtering medium but have clogged at the first pressing, and from then on the water could only escape as steam or past loose fitting pistons. 25 It is, therefore, an object of this invention to provide an improved vertical hydraulic press adapted to form the article in a horizontal position to avoid segregation.

It is also an object of this invention to 30 provide an improved filtering medium having a series of parallel hair line slots adapted to permit ready cleaning by brushing lengthwise of the slots.

This invention (in a preferred form) is 35 illustrated in the drawings and hereinafter more fully described.

On the drawings:

Figure 1 is an elevation of a hydraulic press embodying the features of the invention.

Figure 2 is a top plan view thereof.

Figure 3 is a section on the line III—III of Figure 1 showing the piston head in plan view.

Figure 4 is a section on the line IV—IV of Figure 3 showing the piston passage.

Figure 5 is an enlarged plan view of the filtering plate with the width of the slots greatly exaggerated.

Figure 6 is a top plan view of the piston with the filtering plate removed.

Figure 7 is a fragmentary section of the filtering plate taken on the line VII—VII of Figure 5.

As shown on the drawings:

A vertical hydraulic press is shown comprising a top head 10, cored at 11 for a steam pocket supplied by the pipe 12. The head 10 is tied to a base 13 by rods 14, the base having the usual hydraulic cylinder bore 15 with a hydraulic ram 16 therein, with a suitable packing gland 17 surrounding the ram. The operating fluid is supplied through a pipe 18 and check valve 19 to a lever operated pump 20 supported on a bracket 21, the pump discharging through a check valve 22 to the inlet 23 to the hydraulic cylinder 15, by suitable piping 24 including a pressure gauge 25 and release valve 26. In commercial use the press 70 would probably be operated directly from a high pressure fluid supply line but a hand pump has been illustrated to complete the showing.

A press cylinder 28 is suspended from 80 the top head 10 and contains a removable form or die 29 therein conforming to the shape of the article to be produced. Below the die a stock inlet port 30 has a stock plunger valve body 31 and pipe connection 85 32 mounted thereon, the valve plunger 33, lever 34, and lock screw 35 being indicated. An air vent is also provided from the cylinder 28, a lever plug 36 therefor together with a locking bracket 37 being shown in 90 Figure 1.

The press piston is of special construction and is bolted on top of the ram by the flange 38, the enlarged piston section 39 making a close fit in the press cylinder 28. The form 95 of the cylinder die, and piston section of course varies with the article to be produced, a plain circular form being shown such as is suitable for the production of stool seats. The top of the piston proper is provided 100 with a series of interconnected concentric ring grooves 40 communicating with a central cored passage 41 having a cross passage 42 with connections at both ends, one adapted to create a vacuum in the ring grooves 105 and the other for drainage purposes. Suitable flexible hose may be used for the connections.

A filter plate 43 is secured to the piston top over the ring grooves and contains a 110 large number of short parallel hair line slots 44 which, as shown in Figure 7, are

tapered so that any material entering the slot will easily pass completely through and thereby avoid clogging the filter. Further, the use of parallel slots instead of woven screens permits ready cleaning by using a bristle brush in the direction of the slots, the bristles of a brush readily entering and removing material therefrom.

The piston head is also provided with cored passages 45 for steam heating the piston.

In the operation of this machine the piston is raised into the cylinder to a height necessary to make the final product the right thickness, the pulp stock averaging several times as much water as fibre. The pulp valve and air vent are then opened and the space in the cylinder between the die and piston top completely filled with pulp, whereupon the pulp valve and air vent are closed.

The steam supply is maintained constant to the top head of the hydraulic press and in the piston head also if desirable for the article to be made.

Upon applying further fluid pressure to the ram it rises and the water in the pulp is forced through the filter plate slots and drained away. A vacuum is then created beneath the filter plate, or alternatively, a vacuum may be also used during the initial draining period. It is, however, more economical to allow the major part of the water to drain away before applying the vacuum, which then serves to draw off the steam generated in the compressed pulp by the heating from the steam jackets or cored passages. The use of a vacuum at this stage accelerates the baking or drying operation and prevents sogging of the product.

It will thus be seen that I have produced an improved and simplified mechanism for producing articles from compressed paper pulp.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. In combination with a hydraulic press a cylinder a form therein, a piston adapted to enter the cylinder, a series of connected grooves in the top surface of said piston, a slotted filter plate secured above said grooves, and a connection from said grooves to a source of sub-atmospheric pressure.

2. In combination with a hydraulic press a cylinder a form therein, a piston adapted to enter the cylinder, a series of connected grooves in the top surface of said piston, cored steam passages in said piston, a slotted filter plate secured above said grooves, and a connection from said grooves to a source of sub-atmospheric pressure.

3. In combination with a hydraulic press a cylinder, steam compartments in the head of said press, a form therein, a piston adapted to enter the cylinder, a series of connected grooves in the top surface of said piston, a slotted filter plate secured above said grooves, and a connection from said grooves to a source of sub-atmospheric pressure.

In testimony whereof I have hereunto subscribed my name.

EDWARD HUTCHENS.
